CLAIM

The ornamental design for a screwdriver bit with combination Phillips and blade tip, as shown and described.

DESCRIPTION

FIG. 1 is a top, front, left side perspective view of a screwdriver bit with combination Phillips and blade tip, showing my new design;

FIG. 2 is a left side elevational view thereof, the right side being a mirror image thereof;

FIG. 3 is an, top plan view thereof, the bottom plan view being a mirror image thereof;

FIG. 4 is an, front elevational view thereof; and,

FIG. 5 is a rear elevational view thereof.

The characteristic ornamental feature of my new design resides in the pyramidal point protruding from the end of the blade.
